UNITED STATES PATENT OFFICE.

LOUIS W. WERNER, OF ST. LOUIS, MISSOURI.

IMPROVEMENT IN HYDRANTS.

Specification forming part of Letters Patent No. **85,879**, dated January 12, 1869.

To all whom it may concern:

Be it known that I, LOUIS W. WERNER, of St. Louis, in the county of St. Louis and State of Missouri, have invented new and useful Improvements in Hydrants; and I do hereby declare that the following is a full, clear, and exact description thereof, which will enable those skilled in the art to make and use the same, reference being had to the accompanying drawings, forming part of this specification, in which the drawing represents a central vertical section of my improved hydrant, the middle part being broken away to bring both ends of the hydrant within the limits of the sheet.

The object of this invention is to provide a hydrant which is simple, effective in its operation, and easily taken up to repair or clean out when occasion requires.

The parts shown in red are accessory to the working of the parts claimed as new.

The barrel of the hydrant is shown at L, and may be the common-sized gas-pipe used within buildings.

The valve-chamber U is formed with a lateral chamber, D, cast on it, and communicating with the valve-chamber by ports b b, as shown.

The valve C (having a socket, E, for the valve-rod G) is composed of leather washers, encircling the socket E, and clamped against the socket by means of a nut, as shown.

The chamber U terminates in a conical extension, B, which is cast on the said chamber, and which fits water-tight within a corresponding conical seat, A, having three lugs, J J. This seat is affixed to the water-pipe in the ground by any suitable means, as a screw-thread. A nut, T, unites the hydrant-barrel L with the valve-chamber U, as shown.

Rods H H H, having heads K K, pass through the lugs J J on the seat A, and also through similar lugs J J' on the head-sleeve Q, which latter is screwed onto the upper end of the hydrant-barrel L, as shown.

The valve-rod G is affixed within the socket E' of the swivel-coupling, which works on the reduced end of the screw-stem N, as shown, which latter passes through the cap P and works with a thread within the head Q, as shown.

In practice, the hydrant is put in by inserting the conical end B in its seat A and screwing up the nuts M M, which clamp the hydrant-barrel and its attachments to the seat A, and thus form a water-tight joint.

By turning the crank-handle O the valve C is raised from its seat, as shown, and the water permitted to pass into the chamber D and return again to the chamber U above the valve, whereby the water may flow uninterruptedly. When the valve is raised the waste-water hole a is closed; but when the valve is seated the said hole is left open to permit the egress of the water left in the barrel below the spout I. The lower face of the valve, when the latter is seated, closes the connection with the valve B, and the side surface of the valve also closes the lower opening, b, thus doubly securing the hydrant from leakage.

When the interior of the hydrant-barrel or the valve-chamber needs cleaning, or any part requires repair or readjustment, the hydrant-barrel and its attachments can be withdrawn without the labor of digging up the hydrant, as is usually the case under such circumstances, for the nuts M M have only to be unscrewed, when the barrel L and chamber U can be withdrawn from the ground.

The hydrant is simple and of small cost, and is seldom out of repair.

I claim as new and desire to secure by Letters Patent—

The combination and arrangement of the valve-chamber U and head Q with the conical seat A and screw-rods H, when the conical end B of the valve-chamber is adapted to fit into the seat A and the valve C held above said end, whereby the water entering the latter passes around and above the valve into the barrel L, as herein described, for the purpose specified.

The above specification of my invention signed by me this 15th day of February.

LOUIS W. WERNER.
